UNITED STATES PATENT OFFICE.

MAURICE C. SHELTON, OF INDIANAPOLIS, INDIANA, ASSIGNOR TO SHELTON VAPOR STOVE COMPANY, OF INDIANAPOLIS, INDIANA.

NEEDLE-VALVE CONTROL OF OIL STOVES.

Application filed July 7, 1923. Serial No. 650,122.

To all whom it may concern:

Be it known that I, MAURICE C. SHELTON, a citizen of the United States, residing at Indianapolis, in the county of Marion and 5 State of Indiana, have invented new and useful Improvements in Needle-Valve Controls of Oil Stoves, of which the following is a specification.

It is the object of my invention to provide 10 a stove of the arrangement so as to permit the use of a volatile hydrocarbon fuel, such as gasoline, in the preliminary heating of a vapor generator, and the use of a less volatile hydrocarbon fuel, such as kerosene, 15 after such preliminary heating has progressed to the temperature whereby the less volatile fuel will be readily vaporized.

To accomplish this purpose, it is the particular object of my invention to control the 20 flow of the two liquid fuels through suitable piping and a single valve for each burner of the stove, in such manner that either fuel may be used selectively through such valve and the rate of flow of either fuel be controlled and indicated.

I accomplish the foregoing and other objects which will hereinafter appear, by the means illustrated in the accompanying drawings, in which—

30 Fig. 1, is a plan view of my dual control valve as attached to the fuel supply pipes; Fig. 2, a front elevation of my dual control valve; Fig. 3, a side elevation of the fuel pipe which connects the valve to the vapor generator; Fig. 4, an elevation of my control valve-plug; and Fig. 5, a vertical section of my control valve taken on the line 5—5 of Fig. 1.

Like characters of reference represent like 40 parts throughout the several views of the drawing.

A tank 5 is provided with the partition 6, so that a storage of gasoline is provided in one end of the tank and kerosene in the other. The tank 5 is suitably mounted on 45 the back of the hood 7 and above the plane of the stove top 8. The grid 9 is supported by the stove top 8.

The separate fuels flow by gravity down 50 from tank 5, through the pipes 10 and 11 to the opposite sides of the valves 12, as indicated.

The valve 12 is rigidly connected to pipes 55 10 and 11 by means such as the union nuts 13. The valve 12 comprises the body 14,

having a central conically tapered seat in which the valve plug 15 closely contacts. Intimate contact, such as to prevent leakage of the liquid fuels, of the valve plug 15 with its seat in valve-body 14, is secured by a 60 downward pull on the valve plug 15 by the spring 16, which is compressed between the washer 17, bearing on the body 14, and the washer 18, which is retained by cotter-pins 65 engaging in the holes 19 in the valve plug 15. The valve plug 15 has the ports 20 and 21 drilled transversely, opening into the central vertical passage 22. This central passage 22 extends downward, forms the needle valve seat 23, and terminates in the 70 nozzle 24.

Fitted in this central passage 22, above the port openings 20 and 21, by fine screw threads, is the needle 25, which may be rotated by the knurled-head 26 carrying an 75 indicating point 27. The liquid fuel is prevented from passing up around the needle 25, by suitable packing 28, compressed by the packing-nut 29.

Formed, preferably integral, with the upper end of the valve plug 15, is the indicating dial 30. The valve plug 15 may be rotated in the seat of the valve body 14, by a suitable handle 31, secured to the valve 80 plug 15 by the screw 32.

To operate the stove, I bring all valve handles 31, to the outward position at right angles to the supply pipes 10 and 11. The compartments of the tank 5 are filled with gasoline and kerosene. I turn all adjusting 90 heads 26 to the left (downwardly) continuing such rotation until the needles 25 firmly rest on the needle valve seats 23.

Selecting that burner, which I desire to operate, I turn valve handle 31 to the right until valve plug 21 coincides with the valve-body port 33, as in Fig. 5. This point of coincidence is pre-determined by means of the lug 34 on the valve plug 15, coming into contact with such a shoulder or stop 35, as indicated in Fig. 2, in another point of port coincidence. Gasoline will flow from its 95 respective compartment in tank 5 through pipe 11, through valve-body port 33, and valve plug port 21, into the central passage 22 of valve plug 15.

I then turn the adjusting head 26, to the right slightly, such that the indicating point 27 comes between the numerals 10 and 20, on the dial 30, as shown 100 in Fig. 1. I have shown the dial 30 gradu- 105 110

ated to correspond to the number of drops of the liquid fuel per minute, although it can be otherwise graduated, arbitrarily. Upon the adjustment of head 26, as above 5 stated, the gasoline will pass over needle valve seat 23 and drop from nozzle 24 at the rate of between 10 and 20 drops per minute.

Attached to the valve body 14, by screw threads 36, Figs. 2 and 3, is the generator 10 supply pipe 37. The gasoline drops from the nozzle 24 into this supply pipe 37, and flows by gravity to the burner generator cup not shown. The pipe 37, is cut away as at 39, Fig. 2 and Fig. 3, to permit observation 15 of the flow of fuel as it drops from the nozzle 24. When the gasoline flows into the cup, it may be ignited, and with a suitable burner (not shown) the heat of combustion produces a vapor which burns with intense 20 heat and a non-luminous flame.

The burner may be continuously operated on gasoline as above indicated, but I find it more preferable to use kerosene after pre-heating the burner as described. To so 25 operate, I turn the handle 31 to the left until lug 34, Fig. 2, contacts with stop 35. In this position the port 20 of the valve 30 plug 15 coincides with the port 40 of the valve-body 14, Fig. 5.

The port 33 of the valve-body is thus 35 closed by the wall of the valve plug 15. The flow of gasoline is stopped and kerosene flows from its compartment in tank 5 through pipe 10, valve-body port 40, down through 40 valve plug 15 and drops from nozzle 24. I find that the adjusting head 26 must be turned further to the right, that is lifting the needle 45 from its seat 23, in using kerosene in place of gasoline on account of the difference in viscosity.

In using either fuel, the adjusting head 26 may be turned to raise or lower needle 50 25 and so regulate rate of flow of the fuel, and hence regulate the amount of heat produced at the burner. For instance, in practice, the adjusting head may be turned to point 20 on the dial 30, to produce a low 55 heat, or to point 60 to produce an intense heat, depending upon the will of the operator.

While I have here shown the best embodiment of my invention now known to me, it is capable of variations without departing from the spirit of the invention and I therefore 60 do not desire to be limited to the precise forms shown, nor to the use of fuels mentioned, nor any more than is required by the appended claims, and having fully described my invention what I claim is:—

1. In an oil stove, a dual control valve, having a valve plug with ports of channels

passing transversely through the valve plug to a central vertical passage in said valve plug, said valve plug having a central vertical passage through a depending nozzle at 65 the lower end; a needle valve in the valve plug readily adjusted from without the valve independently of valve plug rotative position; and a means of packing around the needle valve within the central passage 70 of plug.

2. In an oil stove, an indicating needle control valve, having a valve plug with ports of channels passing transversely through the valve plug to a central vertical 75 passage within said valve plug; a downward, depending nozzle through which the central vertical passage of said valve plug passes; a needle valve within the valve plug, readily and independently adjustable from 80 without the dual control valve; means of packing around the needle valve needle; stops to limit rotation of said valve plug; and a handle attached to said valve plug.

3. In an oil stove, a valve-body having a 85 valve plug with a central passage with ports of channels entering transversely therein, and having a valve plug with depending nozzle; an externally adjustable needle valve in a central passage of said valve plug, 90 said plug being held in contact with the valve-body seat by a spring; an indicating dial; and an indicating pointer movable over said dial.

4. In an oil stove, a dual control valve 95 body having transverse passages therethrough; parallel fuel pipes intercepting the passages of said valve body; a valve plug conically seated in the control valve body, said valve plug having ports to register selectively with ports of the transverse 100 passages in the said valve body, and channels from said valve plug ports entering a central vertical passage within the valve plug; a downwardly depending valve plug nozzle; means of limiting said valve plug rotation; a dial integral with said valve plug and rotating therewith; an adjusting 105 needle valve within the central passage of said valve plug; a needle valve adjusting head; an indicator on said adjusting head; a valve plug handle; means of compressively seating said valve plug on its seat; means 110 of packing around the needle valve stem; and a fuel discharge pipe extending from the depending nozzle of said valve plug; and means in said discharge pipe for observation of the flow of fuel from said depending nozzle.

Signed at Indianapolis, Indiana, this the 120 25th day of June, 1923.

MAURICE C. SHELTON.
